DOUBLE FACED NECKTIE OR
FOUR-IN-HAND

Manuel Lucas, New York, N. Y.

Application March 2, 1936, Serial No. 66,725

4 Claims. (Cl. 2-146)

This invention relates to improvements in neckties, and has particular reference to double faced ties which are intended to be worn with either face and either extremity thereof exposed to view.

5 An object of this invention is to make the knot making portion of a lined double face tie thinner at the side edges by reducing the width of the lining to less than the width of the face members of the tie at said portion.

10 Another object of this invention is to have the lining at the knot making portion loose or unconnected with the face members so that the stitched side edges thereat will not be as thick as the rest of the side edges having the lining 10 stitched therein and so as to permit easy slipping of the tie when making a knot and also to prevent the knot from being too bulky.

15 Another object of this invention is to place said unconnected lining portion in offset relation with the longitudinal mid portion of the tie.

20 With the above and other objects in view, the invention will be hereinafter more particularly described, and the combination and arrangement of parts will be shown in the accompanying drawing and pointed out in the claims which form part 25 of this specification.

Reference will now be had to the drawing, wherein like numerals of reference designate corresponding parts throughout the several views, 30 in which:

35 Figure 1 is a longitudinal sectional view of a necktie with one of the face members removed and showing the lining stitched to the other face member along the side edges, except at a knot making portion.

Figure 2 is a plan view of the necktie shown in Figure 1, as it appears when completely assembled.

40 Figure 3 is a cross-sectional view, the section being taken as on line 3-3 in Figure 2.

Figure 4 is a cross-sectional view, the section being taken as on line 4-4 in Figure 2.

45 Figure 5 is a longitudinal sectional view of a modified necktie having two unstitched knot making portions in the lining of the necktie.

In the illustrated embodiments of the invention, the several views show a necktie or four-in-hand intended to be worn with either face member exposed to view. The face members of the 50 tie 10 may be made of any suitable material, such as silk, and the material will preferably be cut on the bias so that the body of the tie will be more or less elastic in character. The body of the tie may comprise a narrow neck portion 11 and tapering or V-shaped ends 12 and 13.

A bias cut lining 14 made of buckram, linen or other suitable material is shown in Figure 1 as connected at both side edges thereof by stitching 15 and 16 to the face members 17 and 18, as is best shown in Figure 4. The lining is made of material which is adapted to withstand the pulling strain to which it is subjected after having yielded lengthwise with the body material to a small extent, and so that when the pulling strain is relieved, the fabric covering and the lining 10 material will resume their original shape. The face member 18 is shown in Figure 2 as having thereon a diagonal seam 19, near the middle of its length, as is usual in four-in-hands.

The two face members of the tie are taken 15 from differently or dissimilarly ornamented layers of material. These face members although substantially of the same size and shape, are complementary rather than identical. The tie 10 is formed by placing a lining of the same size and 20 shape as the covering members upon two complementary fabric covering sections lying face to face and sewing their edges together. The tie thus formed is then turned inside out in order to conceal the seams and expose the normally 25 exposed faces of the goods.

The two face members may be used interchangeably as the front and rear faces of the tie. The two faces may provide two different patterns or two different colors or materials of 30 two different textures so as to produce the same effect as could be obtained by the employment of two different ties, thereby effecting economy and providing convenience in the use of four-in-hands.

As shown in Figures 1 and 3, the width of the 35 lining 14 has been reduced at the knot making portion 20. The reduced lining portion, identified by the numeral 21, is of sufficient length to permit the formation of a knot thereat and is entirely unconnected with the face members 17 40 and 18. The portion 20, best shown in Figure 3, is of less thickness than the rest of the necktie, as shown in Figure 4.

Figure 5 shows a modified necktie or four-in-hand 45 22 having two lining portions 23 and 24 of less width than the overall widths 25 and 26 of the assembled necktie. This modified necktie permits either extremities 27 or 28 to be used as, a knot making end. The modified necktie 22 is made and assembled in the same way as the 50 necktie 10.

Due to the resilience of the bias cut face members and the bias cut lining, the neckties here-with disclosed will withstand considerable rough handling without losing their shape.

- It is to be noted that the three members making up the necktie are stitched together on the normally concealed sides of the face members and that when the necktie is turned inside out, the normally exposed faces come into view and the stitching at the side edges becomes concealed inside the necktie, the side edges showing a line of infolding of the two face members but no stitching whatever is visible at the side edges.
- 10 It is to be noted that the necktie lining may comprise one or more layers, as is the case when thin covering material is used for summer wear.
- I claim:
- 15 1. A three-ply necktie or four-in-hand comprising a fabric covering of two dissimilarly ornamented face members and a lining stitched together along both side edges, said lining having an unstitched knot making portion of less width than the width of the covering members of the tie at said portion, said narrow width lining portion being unconnected with said face members and being in offset relation with the longitudinal mid-portion of said tie, said fabric covering and said lining being of the same length and the stitching along the side edges being concealed inside the tie.
- 20 2. A three-ply necktie or four-in-hand having thereon a fabric covering made of two dissimilarly ornamented blanks of the same size and shape by means of two seams lengthwise thereof, a lining of the same size and shape as the covering members secured at both side edges thereof by said seams to said covering interiorly of the latter, at least one portion on said lining in offset 30 relation with the longitudinal mid-portion of the necktie being reduced in width lengthwise thereof, whereat said tie may be readily formed into a knot without undue bulkiness, said fabric covering and said lining being of the same length and the stitching along the side edges being concealed inside the necktie.
- 25 3. A three-ply or four-in-hand necktie having thereon a fabric covering comprising two separate and dissimilarly ornamented members which may be interchangeably used as the front and rear of the necktie, a lining stitched to said fabric covering members along their side edges, said necktie terminating in V-shaped closed ends with the lining ends secured by stitching to said face members, at least one portion of said lining in offset relation from the longitudinal mid-portion of the necktie being loose and unconnected and in semi-floating relation intermediate said front and rear face members, said fabric covering and said lining being of the same length and the stitching along the side edges being concealed inside the necktie.
- 30 4. A necktie or four-in-hand having thereon a fabric covering comprising two separate and dissimilarly ornamented members of the same size and shape which may be interchangeably used as the front and rear of the necktie, lining means of the same size and shape as the covering members secured at both side edges thereof by seams to said covering interiorly of the latter, said necktie terminating in V-shaped closed ends with the ends of the lining means secured by stitching to said covering members, at least one portion on said lining means being reduced in width lengthwise thereof and free from attachment to said covering, whereby said tie may be readily formed into a knot without undue bulkiness, said fabric covering and said lining means being of the same length and the stitching along the side edges being concealed inside the necktie while the stitching along the V-shaped ends is exposed.

MANUEL LUCAS.
